AIRCRAFT FLIGHT INSTRUMENT

Raymond W. Sargent, Burlington, Vt., assignor to Simmonds Precision Products, Inc., a corporation of New York

Filed Oct. 28, 1960, Ser. No. 62,656

Term of patent 7 years

(Cl. D52—6)

FIG. 1.

FIG. 2.

FIG. 1 is a front elevational view of an aircraft flight instrument showing my new design;

FIG. 2 is a perspective view thereof; and

FIG. 3 is a fragmentary view showing a part of the housing in side elevation taken from the left of FIG. 2.

The characteristic features of the design for the instrument disclosed reside in the scale features of the dial face having the configuration shown.

I claim:

The ornamental design for an aircraft flight instrument, as shown.
